ATTORNEY

UNITED STATES PATENT OFFICE.

STEPHEN T. STOUT, OF CEDAR GROVE, GEORGIA.

CHURN-OPERATING MECHANISM.

SPECIFICATION forming part of Letters Patent No. 236,379, dated January 4, 1881.

Application filed June 5, 1880. (No model.)

To all whom it may concern:

Be it known that I, STEPHEN T. STOUT, of Cedar Grove, in the county of Walker and State of Georgia, have invented certain new and useful Improvements in Churn-Operating Mechanism; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a rear elevation of my device. Fig. 2 is a side view, and Fig. 3 is a view of the dasher. 15 My invention relates to a churn-operating machine; and it consists in the features of construction and combination, as will be fully set forth in the following description and particularly pointed out in the claims.

20 In the drawings, A designates a table, under which the churn is to be placed during the operation of churning. The table is supported by two pairs of legs, B, these legs being formed with slots C and crossed, so as to admit of the bolts D being passed through the slots C. The bolts are secured to plates E at one end, and passed through flanged plates e at their remaining ends, nuts F being employed to tighten up the plates against the legs. By this means 25 the table can be raised or lowered by loosening the nuts and shifting the position of the bolts in the slots of the legs, the latter being expanded or contracted, according to the direction in which the bolts are shifted. Upon the 30 table are secured two standards, G G, which are connected at their top ends by an arch, H. Between the arch and the table are two pairs of horizontal bars, I I, in the upper pair of which is journaled the shaft of a gear, K, and 35 in the lower pair is journaled the shaft of a smaller gear, L, which intermeshes with the larger gear K. Upon the shaft of the upper gear is a handle, M, by means of which motion may be imparted to the said gear. On the 40 shaft of the lower and smaller gear is a wheel, 45

N, to which is pivoted a rod, P. This rod connects at its upper end with a slide, R, which works vertically between two guide-bars, S S, these bars being secured at their lower ends to a block, T, upon the metal plate T', which is 50 embedded in the table. The spokes of the wheel N have holes N', so that the pivot of the rod P may be transferred to a position nearer to the center of the wheel when desired, thus making a shorter stroke of the dasher-rod U, which is 55 secured to the slide.

The dasher V is formed similarly to an ordinary propeller-wheel, and is arranged loosely upon the lower end of the dasher-rod, whereby, as it is raised or lowered through the cream in 60 the churn, it will have partial rotations.

W. is a bar, secured at one end to the arch of the standards, and also secured at its remaining end to the upper ends of the guide-bars S S. 65

What I claim, and desire to secure by Letters Patent, is—

1. The combination of a churn-operating mechanism with the table A, the legs B, with slots C, the bolts D, passed through said slots, 70 the plates E e, and the tightening-nuts whereby the table can be raised or lowered, substantially as shown and specified.

2. In a churn-operating mechanism, the combination of the table A with the standards G, 75 arch H, at the upper ends of the standards, the horizontal bars I, gears K L, having their shafts journaled in the horizontal bars, the wheel N, connecting-rod P, and slide R, connecting with the dasher-rod and arranged to move vertically between the guide-bars S, substantially as specified.

In testimony that I claim the above I have hereunto subscribed my name in the presence of two witnesses.

STEPHEN T. STOUT.
